FIG. 9 is a side view of the aerosol dispenser of FIG. 1 in open position;

FIG. 10 is a top view of the aerosol dispenser of FIG. 1 in open position;

FIG. 11 is a perspective view of a second embodiment of an aerosol dispenser in closed position, embodying our new design;

FIG. 12 is a front view of the aerosol dispenser of FIG. 11; FIG. 13 is a back side view of the aerosol dispenser of FIG. 11;

FIG. 14 is a right side view of the aerosol dispenser of FIG. 11;

FIG. 15 is a left side view of the aerosol dispenser of FIG. 11;

FIG. 16 is a top view of the aerosol dispenser of FIG. 11; FIG. 17 is a bottom view of the aerosol dispenser of FIG. 11; FIG. 18 is perspective view of the aerosol dispenser of FIG. 11 in open position;

FIG. 19 is a side view of the aerosol dispenser of FIG. 11 in open position;

FIG. 20 is a top view of the aerosol dispenser of FIG. 11 in open position;

FIG. 21 is a perspective view of a third embodiment of an aerosol dispenser in closed position, embodying our new design;

FIG. 22 is a front view of the aerosol dispenser of FIG. 21; FIG. 23 is a back side view of the aerosol dispenser of FIG. 21;

FIG. 24 is a right side view of the aerosol dispenser of FIG. 21;

FIG. 25 is a left side view of the aerosol dispenser of FIG. 21;

FIG. 26 is a top view of the aerosol dispenser of FIG. 21; FIG. 27 is a bottom view of the aerosol dispenser of FIG. 21; FIG. 28 is perspective view of the aerosol dispenser of FIG. 21 in open position;

FIG. 29 is a side view of the aerosol dispenser of FIG. 21 in open position;

FIG. 30 is a top view of the aerosol dispenser of FIG. 21 in open position;

FIG. 31 is a perspective view of a fourth embodiment of an aerosol dispenser in closed position, embodying our new design;

FIG. 32 is a front view of the aerosol dispenser of FIG. 31; FIG. 33 is a back side view of the aerosol dispenser of FIG. 31;

FIG. 34 is a right side view of the aerosol dispenser of FIG. 31;

FIG. 35 is a left side view of the aerosol dispenser of FIG. 31;

FIG. 36 is a top view of the aerosol dispenser of FIG. 31; FIG. 37 is a bottom view of the aerosol dispenser of FIG. 31;

FIG. 38 is perspective view of the aerosol dispenser of FIG. 31 in open position;
FIG. 39 is a side view of the aerosol dispenser of FIG. 31 in open position;
FIG. 40 is a top view of the aerosol dispenser of FIG. 31 in open position;
FIG. 41 is a perspective view of a fifth embodiment of an aerosol dispenser in closed position, embodying our new design;
FIG. 42 is a front view of the aerosol dispenser of FIG. 41;
FIG. 43 is a back side view of the aerosol dispenser of FIG. 41;
FIG. 44 is a right side view of the aerosol dispenser of FIG. 41;
FIG. 45 is a left side view of the aerosol dispenser of FIG. 41;
FIG. 46 is a top view of the aerosol dispenser of FIG. 41;
FIG. 47 is a bottom view of the aerosol dispenser of FIG. 41;
FIG. 48 is perspective view of the aerosol dispenser of FIG. 41 in open position;
FIG. 49 is a side view of the aerosol dispenser of FIG. 41 in open position;
FIG. 50 is a top view of the aerosol dispenser of FIG. 41 in open position;
